CLAIM

The ornamental design for a combined astragal extrusion and seal, as shown and described.

DESCRIPTION

FIG. 1 is a perspective view, of indeterminate length, showing my new design for a combined astragal extrusion and seal;

FIG. 2 is an elevational view of the visible end, as shown in FIG. 1

FIG. 3 is a fragmentary front side elevational view of the same;

FIG. 4 is a fragmentary rear side elevational view;

FIG. 5 is a fragmentary top plan view; and

FIG. 6 is a fragmentary bottom plan view.
